UNITED STATES PATENT OFFICE.

WILLIAM PATTON, OF CINCINNATI, OHIO, ASSIGNOR TO THE PATTON BIN & FIXTURE COMPANY, OF CINCINNATI, OHIO, A CORPORATION OF OHIO.

DISPENSING APPARATUS.

1,252,022.

Specification of Letters Patent. Patented Jan. 1, 1918.

Application filed July 28, 1916. Serial No. 111,865.

To all whom it may concern:

Be it known that I, WILLIAM PATTON, a citizen of the United States, and a resident of Cincinnati, in the county of Hamilton and State of Ohio, have invented certain new and useful Improvements in Dispensing Apparatus, of which the following is a specification.

My invention relates to dry measurers, and its object is to facilitate accurate measurement of quantities of granular materials or similar commodities with regard to their weights and specific gravities as well as to their values or prices; being an improvement upon my invention disclosed and claimed in my Patent No. 1,193,180, of August 1, 1916.

My invention consists of the combination of parts, and of the details of construction and arrangement of parts as will hereinafter be more fully described and claimed.

In the drawing:

Figure 1 is a front perspective view of a set of bins provided with my invention;

Fig. 2 is a partial rear perspective view of the same;

Fig. 3 is a general perspective view of my invention from the rear of the bin as in Fig. 2, considerably enlarged, and with parts of the bin omitted and other parts of the device inside the bin indicated by dotted lines;

Fig. 4 is another rear view but with all but a small top part of the rear plate broken away to clearly disclose the rear end construction of the dispensing apparatus;

Fig. 5 is a longitudinal vertical section of the apparatus on a plane corresponding to the line 5—5 of Fig. 4; and

Fig. 6 is a plan view of the device with the hopper and connecting parts omitted.

In the example of the use of my invention as herein shown, a bin 1 is provided, which may be of well known construction with transparent sides in its upper part for displaying the contents, and a bottom section 2 below, which contains the sloping bottom or hopper 3 with a downwardly projected outlet neck 4 through which the contents of the bin may be discharged. It will be understood that any suitable container for the commodity may have an outlet similar to

the neck 4; the prime purpose of the invention being to so control and regulate the discharge from the neck 4 that any desired quantity or weight of the commodity may be secured by simple manipulation and with the liability for inaccuracy and mistakes minimized.

One of the important improvements over my previous invention above alluded to, however, is in the arrangement of the dispensing mechanism with its greatest length from front to rear of the bin rather than across the rear thereof. This allows the bin to be narrower; which is a great advantage in affording economy of space in stores, because the bin is best made of a length from front to rear about the same as the width of the counter from front to rear, and for the most desirable capacities a bin of this length need not be very wide.

As indicated in Figs. 1 and 2, I prefer to make the bin 1 with two compartments and with one of my improved dispensing apparatus for each compartment. With the new arrangement above alluded to, the two-compartment bin need be but very little wider than would be a single compartment provided with my device as previously constructed.

The dry-measuring device, as exemplified herein, comprises sides 5 and 6 and an end 7, making up a framework of rectangular general formation. The end 7 is at the rear of the bin, and the other end of the framework is held together by upper and lower struts 8 and 9. The upper edges of the sides 5 and 6 are flat, and form a runway for the slide 10, which has its upper and lower sides smooth, and is held down by rabbed strips 11 screwed to said upper edges and overlapping the rabbed edges of the slide. The end 7 is set in forwardly from the rear ends of the sides 5 and 6, and its upper part slopes downwardly and backwardly into a spout 12, the use of which will be later described. Mounted upon the strips 11, over the slide 10, is a rectangular inlet neck 13.

The apparatus is mounted to be slid backwardly out of the bin so as to give ready access to its mechanism, for adjustment or

repairs. As here shown, a pair of supporting bars 14 are fixed in the lower part of the bin longitudinally thereof from front to rear, and extension bars 15 slide upon the tops of the bars 14, having, under their front ends, heads 16 embracing the bars 14 and forming stops against complete withdrawal of the bars 15 when these heads strike the brackets 17 and 18 that support the rear 10 ends of the supporting bars 14 in the bin. The framework has lugs 19 fixed on its bottom and straddling the extension bars 15, which latter have at their ends stops 20 that cause the extension bars 15 to slide out with 15 the apparatus, after which the apparatus may be lifted off the bars 15.

The inlet neck 13 makes sliding tongue-and-groove connection with the neck 4 of the hopper 3 when the framework is slid 20 into place in the bin. In order to close the neck 4 when the framework is to be slid out of the bin, this neck is provided with an auxiliary slide 21 that is normally pulled out of the neck 4 forwardly, and is supported in that position by an arm 22 extending forwardly from one side of the neck 4.

To properly discharge the contents of the bin down through the neck 4 into the space between the sides of the framework, where 30 it is measured as will hereinafter be described, I prefer to provide an agitator in the neck 4. As here shown, this comprises a shaft 23 running longitudinally of the interior of the neck 4 from front to rear, and 35 having bearings 24 and 25 in the front and rear ends, respectively, of the neck 4, and having a series of radiating teeth 26 at intervals throughout its length inside the neck. In front of its bearing 24, this shaft 23 has 40 fixed on it a bevel gear 27, and meshing with this is a bevel gear 28 on a shaft 29, having a bearing 30 in the arm 22, outside which it has fixed on it a spur gear 31, meshing with a rack 32, running parallel with the runway 45 of the slide 10, and with its front end fixed to said slide, and supported and guided at the rear by a guide 33. Thus, pulling the slide 10 forwardly to open communication between the hopper 3 and the space inside 50 the framework, will cause a rotation of the shaft 23 and an agitation, by the teeth 26, of the commodity which might otherwise clog the neck 4, especially if it be a finely pulverized substance.

55 To receive the commodity and measure it, I provide, between the rear end parts of the sides 5 and 6, adjacent to the end 7, means to form a normally empty measuring compartment, with an end adjustable to create and 60 define an empty measuring space in this compartment, and means associated therewith to vary the size of this measuring space proportionally at all adjustments of the adjustable end. Broadly, it is the combina-

tion disclosed and claimed in my co-pending 65 application above referred to; but specifically somewhat less complicated than the specific example of the aforesaid application.

The inner surfaces of these rear end parts 70 of the sides 5 and 6 and of the end 7 are made smooth, and the side 6 has a discharge opening in it which is normally closed by a discharge door 34. Mounted between these 75 smooth parts is the bottom 35, which slopes down toward the discharge opening and is adjustable up and down while making intimate contact with said smooth sides. Next to the side 6, this bottom 35 has an apron 36, so that when the bottom is adjusted above 80 the bottom of the discharge opening, this apron covers the part of the opening below the edge of the sloping bottom.

The sides 5 and 6, end 7, slide 10, and bottom 35 thus form five sides of the measuring space. A flexible curtain 37 has its upper end fixed to the rear end of a carriage 38 that is slideable forwardly and rearwardly on horizontal guides 39 and 40 on the inner surfaces of the sides 5 and 6, respectively. 85 I prefer to make these guides of triangular cross-section to fit in grooves of corresponding formation in the sides of the carriage 38, so that the parts of the guides under the inlet neck 13 will permit the commodity to 95 readily slide off into the measuring space. Also, to prevent clogging of the commodity between the rear end of the carriage 38 and the end 7, I prefer to space the rear ends 41 of these guides 39 and 40 a short 100 distance forwardly from the ends 7, so that the commodity will pass down through the space thus left, when pushed off the ends of the guides 39 and 40 when the carriage is brought back.

The lower end of the curtain 37 is supported by a yoke 42, which has a horizontal part 43 extending back over the bottom 35, and an upright part 44 that embraces and is guided by a column 45, fixed in and projecting down from the carriage 38 far enough forward to clear the front end of the bottom 35 when the carriage is in its rearmost position. The rear end of this yoke 43 has fixed on it a smooth end plate 46 that extends down and has its lower edge closely fitting the entire width of the sloping bottom 35. To maintain this relation, the front end of the bottom 35 is extended down and has fixed in it two forwardly extending guide bars 47, which are embraced by tubular extensions 48 on the yoke 42. Thus, the yoke may slide up and down on the column 45 of the carriage, and may slide forwardly and rearwardly with its end plate 46 bearing closely on the sloping bottom 35 by virtue of its support on the bars 47.

Near the forward end of the yoke 42 its

top is raised above the rear part and supports a plate 49 that forms a rearwardly extending arm having, at its rear end, a sheave-bar 50 which has a convex side presented downwardly and rearwardly. The flexible curtain 37 is brought down under this sheave-bar 50 and pulled forwardly in the space between the rear part of the top of the yoke and the arm or plate 49. The 10 end of the curtain 37 in this space is held between narrow bars 51, which have connected to them, midway of their lengths across the curtain, a flexible member or cord 52, that runs back through an opening 53 in the raised forward part of the yoke top and passes downwardly over a pulley 54 supported on a forward extension 55 at the top of the yoke. The lower end of this cord 52 is connected to the upper end of a tension 20 spring 56, the lower end of which is connected to the lower end of the column 45 that is fixed to the carriage 38; being, as here shown, indirectly connected by being hooked into an opening in a brace 57 that 25 has its lower end fixed to the lower end of said column and its upper end fixed to the forward end part of the carriage 38, this brace being for the purpose of reinforcing the column 45. The upper edge of the end 30 plate 46 is made concave, so as to fit closely enough against the flexible curtain 37, where it passes around the sheave-bar 50, to prevent leakage of commodity between these parts.

35 With the above construction, when the bottom 35 is adjusted upwardly or downwardly, carrying the yoke 42 up or down with it, the curtain 37 will always be stretched tightly from the rear end of the carriage 38 to the upper edge of the end plate 46 by virtue of the yielding tension exerted upon it by the spring 56. This end, thus formed by the curtain 37 and plate 46, is thus adjusted forwardly and rearwardly 40 to vary the length of the measuring space; while it permits the bottom 35 to be adjusted up and down to compensate for variations in specific gravity of different commodities without altering this adjustable 45 end from its required plane conformation. At the same time, there are comparatively few parts to this group, and only one joint added to those at the top, bottom and sides of the adjustable end. The flexible curtain 37 may 50 be woven of fine metal wire or strong closely woven canvas; in either instance giving better service if both upright edges, which must make close contact with the smooth surfaces of the slides 5 and 6, are selvages.

55 The bottom 35 is guided in its upward and downward adjustment by means of an upright channel 58 which it has extending down and fitting on an upright guide 59 fixed to the inner surface of the lower rear

part of the side 5. To move the bottom 35 up and down there is a threaded stud 60 fixed in the lower side of the bottom and extending down and having threaded upon it a nut 61, concentric with and fixed to which is a bevel gear 62 in mesh with the 65 bevel gear 63 on the forward end of a stem 64 that is journaled in a bracket 65, and in a bearing 66 in the end 7. The bracket 65 is fixed in the inner surface of the side 5, and has a forward extension 67 in which the 70 nut 61 is journaled and held against downward and upward movement by the gear 62 above and by a flange 62' on the nut below the extension 67.

75 For moving the slide 10, a shank 68 is fixed on the top of the slide near its front end and extends out over the side 5. The lever 69 extends up along the side 5 and has a fulcrum 70 fixed to said side. The upper end part of this lever 69 has a longitudinal 80 slot 71 receiving the shank 68; and the lower end part adjacent to the bottom of the side 5 has a longitudinal slot 72 which receives the pin 73 fixed in a hub 74, through which extends the forwardly and rearwardly 85 running inlet and discharge rod 75 in such a manner as to turn in the hub but with pins 76 and washers 77 at front and rear of the hub compelling it to move with the rod 75 when this rod is slid forwardly and rearwardly in 90 guide brackets 78 on the outer surface of the side 5 next to its bottom. Thus, if the rod 75 is pulled rearwardly, the slide 10 is pulled forwardly, letting commodity into the measuring space; and a forward push on the rod 75 100 pushes the slide 10 rearwardly and cuts off the inlet of commodity to said space.

95 For moving the adjustable end forwardly and rearwardly to vary the length of the measuring compartment, the carriage 38 has, 105 fixed on its lower side next to the frame side 6, a rack 79 running from the front end of the carriage a sufficient distance backward to cause the maximum required forward movement of the carriage 38 by the rotation of a pinion 80 that meshes with the rack and is fixed on a shaft 81 having a bearing 82 in the side 6 and having fixed on it, outside the frame, a bevel gear 83 in mesh with a bevel gear 84 fixed on a shaft 85 that runs 110 from the front to the rear of the bin and is journaled in brackets 86 fixed on the side 6 near its top, with end-play limited by collars 87.

115 The discharge door 34 has lugs 88 extended outwardly and upwardly from its upper part and embracing the shaft 85, and is thereby hinged to swing outward and upward from the discharge opening in the side 6. Springs 89 are coiled around the shaft 85, 120 each having one end down against the door 34 and the other end hooked over the upper edge of the side 6 to normally hold the door

125

shut. Near its bottom and its rear side, this door 34 has a rearwardly extending stud 90 fitting in the end part of an operating bar 91, which lies across the rear of the end 7 and 5 is guided and supported by a stirrup 92 fixed to the rear edge of the frame side 6. Over adjacent to the other side 5, this operating bar 91 has a downward projection 93, and a finger 94 has a hub 95 by which it is 10 fixed on the inlet and discharge rod 75 for turning therewith as well as sliding rearwardly and forwardly therewith when said rod is slid in this way to operate the slide 10 as above described. This finger 94 is so 15 located on this rod 75 that, when the rod is completely forward and holding the slide 10 in closing position, it is in position for engagement with the rear edge of the downward projection 93 of the operating bar 91. 20 If the rod 75 is turned toward the operating bar 91 as permitted by its hereinbefore described connection with the lever 69, it will cause the finger 94 to push on the operating bar 91 and push the discharge door 34 outwardly and upwardly, and thus permit discharge of the commodity from the sloping bottom 35 out through the discharge opening in the side 6.

As is best seen in Fig. 5, the rear end of 30 the slide 10 is made to project a short distance back of the upper forward edge of the end 7 in its completely closed position; this being defined by the engagement of the hub 95 of the finger 94 with the rear guide 35 bracket 78. This projection is so proportioned to the width of the finger 94 that by the time the rear end of the slide 10 passes forwardly away from said edge of the end 7 on a rearward movement of the rod 75, 40 the finger 94 will have been carried back by this rod out of position for engagement with the projection 93 of the operating bar 91; and this condition will continue to exist throughout all further forward movement 45 of the slide 10, since the finger 94 will be drawn farther back away from the operating bar. Thus, while the rod 75 is used for opening either the inlet slide 10 or the discharge door 34, it cannot be used to open the door while the inlet is open. Thus there is 50 an effective guard against any continuous passage of commodity from the hopper 3 through and out of the measuring compartment during a measuring operation, which 55 continuous passage, if allowed to occur, would result in overweight.

While it is desirable to provide this guard, it is also desirable to be able to conveniently and quickly cause a continuous 60 discharge from the hopper 3 out through the door 34, as for emptying the bin for receiving a different commodity. For this purpose, an auxiliary finger 96 is pivoted on a stud 97 fixed in and extending rearwardly

from the rear edge of the side 5. This auxiliary finger 96 bears against an upward projection 98 on the operating bar 91. Thus, a continuous inlet and discharge are permitted only by an intentional manipulation of a mechanism entirely distinct from that 70 used to cause the consecutive inlet and discharge.

If the slide 10 is started backward before it has had its rear end brought forward to the adjustable end or curtain 37, wherever 75 this end may have been adjusted to, the full inlet of commodity will be interfered with, and this will be very likely to result in underweight. To insure against this, a ratchet bar 99 is fixed on the lower part of the carriage 38 from front to rear, with upwardly presented teeth pitched forwardly, and the slide 10 has a rearwardly projected pawl 100 yieldably held down to engage with these teeth throughout forward travel of the slide 85 10 relative to the ratchet bar 99 until the front end of the slide strikes a stop bar 101 fixed across the carriage 38 near the front end thereof. At this juncture, a lug 102 on the ratchet bar, higher than the teeth 99, 90 raises the pawl 100 so that a nose 103, which it has projecting forwardly, permits a detent 104 to swing rearwardly over it under spring pressure and thus hold the pawl 95 away from the teeth 99 during the return rearward movement of the slide 10. To cause this detent 104 to release this pawl at the beginning of the next opening of the slide 10, a hook 105 swings up and down on a cross piece 106, supported on the strips 11 100 at opposite sides, and has an inclined front end so that it will slide over and engage with part of the detent projecting upward and hold this part back and thus swing the lower end of the detent forward upon forward movement of the slide 10. This construction is fully described and claimed in my hereinbefore referred to patent, and is briefly described as above merely for convenience in understanding the present application. 110

A rearwardly projected foot 107 on the bottom of the end 7 has its side 108 next to the rod 75 and finger 94 broadened from top to bottom except adjacent to the end 7 where 115 it has a recess 109 in its upper edge. This broadened side 108 is brought close enough to the inner side of the finger 94 to prevent turning of the rod 75 in direction to open the discharge door 34, except when the finger 94 is in position to push on the operating bar 91 and thus open the door as hereinabove described. By thus forming a guard against any futile turning of the rod 75 in this direction, the operator may be sure that he has 120 opened the discharge door if he has been able to turn the rod 75 in this direction. The finger 94 also has a downwardly pro- 125

jecting heel 110 which engages with the broad side 108 during all positions of the finger, to limit the opposite turning of the rod 75 and finger 94.

5 This foot 107 has at its rear end an additional bearing 111 for the rod 75, and also has, projecting up, an additional bearing 112 for the stem 64 used to adjust the bottom 35.

10 The back of the compartment in which the dry measuring apparatus is located in the lower section 2 of the bin is composed of a plate 113 which is fastened to the rear end of the foot 107, with an opening registering 15 with a socket 114 formed in the rear of the bearing 112, and the end part 115 of the stem 64 is squared to receive a key for turning the stem.

This plate 113 also has an opening with a 20 tube 116 extending forwardly around the shaft 117 of the auxiliary finger 96, which has a collar 118 bearing against the front end of the tube 116 and holding the finger 96 and its shaft forward on their stud 97, and 25 the rear end part 119 of the shaft 117 is also squared to receive a key, which may be the same one used to turn the stem 64.

The inlet and discharge rod 75 extends through an opening in the plate 113 and 30 has a handle 120 for sliding it or turning it.

The shaft 85 extends through the plate 113, and fixed to the front side of the plate around this shaft is a friction disk 121. A coöperating friction disk 122 is fixed on the 35 front end of a tube 123 around the shaft 85, which tube extends through the disk 121 and plate 113, to slide longitudinally of the shaft 85 within limits permitted by a pin 124 fixed in the shaft and extending out into a 40 short slot 125 in the tube just outside the plate 113. A knurled knob 126 is fixed on the front end of the tube 123, and a spring 127 is coiled around the tube between the knob and the plate 113, so that the disk 122 45 on the tube is normally held backward against the disk 121. The pin 124 in the slide 125 will not permit the shaft 85 to turn without turning the disk 122, the friction of which with the disk 121 will hold the shaft 85 and all of the parts operatively connected therewith, including the adjustable end or 50 curtain 37, from moving except when the knob 126 is pushed forward to lessen this friction.

55 To indicate the adjustment of the adjustable end at the rear, a pointer 128 is fixed on the rear end of a hub 129 that extends through a bearing 130 in the plate 113 and turns on a stud 131 fixed in and projecting 60 back from the end 7. This pointer 128 swings over a scale 132 on the rear side of the plate 113 near its top, which scale can be graduated to indicate weights and values. Preferably, the part of the pointer 128 over

the scale 132 forms a frame for a small glass 65 plate 133, on which is etched a line 134 in proper position to accurately indicate upon the scale 132 the location of the adjustable end. The pointer 128 is caused to move in constant ratio to the movement of the adjustable end by means of a segment gear 135 projecting up from the hub 129 and meshing with a small pinion 136 turning with the shaft 85.

To indicate the adjustment of the adjustable end at the front of the bin, a pointer 137 is fixed on a short shaft 138 (Fig. 3), extending back through a bearing in the front of the lower section 2 of the bin, and having fixed to it a segment gear 139 in 80 mesh with a small pinion 140 upon and turning with the shaft 85. This gear and pinion unmesh to allow withdrawal of the apparatus from the bin.

To indicate the adjustment of the bottom 85 35, a stud 141 is fixed to the bottom and extends out through a slot 142 in the end 7 and a slot 143 in the plate 113, carrying a pointer 144 along an upright scale 145.

Since the slide 10 projects only a short distance back from the upper front edge of the end 7, communication is always left open between the hopper 3 and the spout 12; so that this spout 12 will always contain some 90 of the commodity. Moreover, the space left behind the slide 10 avoids clogging of the slide at the rear termination of its stroke, as disclosed and claimed in my patent hereinbefore mentioned. To further avoid clogging where the slide 10 meets the end 7, the rear end of the slide is preferably beveled upwardly as shown, so that it readily cuts through the commodity in this region.

The purpose of the spout 12 is to facilitate the admission of minute additional 105 quantities of commodity to the charge after it has been measured and discharged from the apparatus, in case the charge is found to be deficient. When the main measured charge passes from the discharge door, it 110 goes into a chute 146 that runs along the exterior of the side 6 and inclines downwardly rearwardly of the rear plate 113, which has an opening through which the chute discharges into a spout 147 that may lead the commodity into the container in which it is to be dispensed, and which container may be on a scale, or the commodity may be discharged from the spout into the 115 pan of the scale; in either case verifying the measurement by actual weighing. The spout 12 also discharges into the chute 146 when its small door 148 is opened upwardly, swinging on a hinge 149.

This opening is effected by means of a 120 small crank shaft 150 that extends through the upper part of the spout just below the hinge 149, with its crank 151 engaging the

under side of the door where it extends slightly past the front side of the spout. The door is normally held closed by a spring 152 mounted on the top of the end part of the spout. The crank shaft 150 extends backward through the plate 113, preferably into a housing 153 on the rear side of the plate, and has a finger piece 154 fixed to it inside this housing, to which access is had by turning the ring 155 around the housing by engagement of the finger with a small lug 156 on said ring, which exposes an opening 157 in the housing through an opening 158 in the ring. A slight pressure on the finger piece 154, by the finger inserted through the opening thus exposed, will open the door 148 the slight distance to permit the very small quantity of additional commodity to pass down into the chute and thence to the main body of the commodity which has been discharged into the container or scale pan. By keeping the finger piece 154 inclosed in the above manner except when it is to be used, tampering by children or others is guarded against. This precaution is desirable in connection with this particular outlet means because it is a directly operated means, whereas the main discharge door 34 can discharge commodity only after the operation of the inlet and cut-off slide 10; and the operation of these means in their proper order to discharge any commodity is not likely to be accomplished by children or others merely tampering with the device and not understanding its correct operation.

It will be understood that the use of an actual weighing scale with my apparatus is not essential; the main reason for such use being the requirement by laws of some States that the commodities be actually weighed and not merely measured. Whether used with an actually weighing device or not, it is possible to so adjust the apparatus that it is possible to dispense commodities with greater accuracy than when the actually weighing device is depended upon alone. The arrangement of two apparatus in a single bin with the spouts 147 adjacent to each other, as shown in Fig. 2, is especially convenient where an actually weighing scale is used in connection with the dispensing apparatus.

Constructed as above described, when it is desired to weigh out a quantity of a commodity, the knob 126 is pushed forward, lessening the friction between the disks 121 and 122, which allows the shaft 85 to be turned freely, thus moving the adjustable end forwardly and creating a measuring compartment in the device ready to receive the commodity. The extent of this forward movement is indicated by the pointer 128 swinging over the scale 132, and the movement is stopped when the pointer lies at the

mark on the scale indicating the weight of 65 the commodity desired.

This having been done, the handle 120 is pulled out toward the operator, which pulls the slide 10 from under the neck 4. This pull on the handle 120 is continued until stopped by the engagement of the front end 70 of the slide with the stop bar 101, upon which and not before, the pawl 100 is disengaged from the teeth 99; whereupon the handle 120 may be pushed in again, returning the slide 10 under the inlet neck 4. During this interval the required amount of commodity will have entered the measuring space or compartment that was formed by adjusting the adjustable end; and now when 80 this quantity of commodity has been completely cut off from the main body of commodity, the finger 94 has again come into position for engagement with the operating bar 91. Then a twist upwardly and outwardly on the handle 20 pushes open the discharge door 34, allowing the measured quantity of commodity to slide out into the chute 146 and be discharged from the spout 147 into a bag or other container in which 90 the commodity is to be dispensed, or, where the scale is used, into the pan in the scale.

If the scale be used and the amount of commodity discharged is not quite enough to make up the desired weight as indicated 95 on the scale, the housing 153 may be opened, giving access to the small lug 156, which when pushed by the finger will open the door 148 of the spout 12 slightly, permitting the desired additional small quantity of commodity to pass into the chute 146 and into the scale pan until the required weight is indicated on the scale.

Should it be desired to empty the bin entirely, the knob 126 is manipulated until the 105 adjustable end is moved forward as far as it will go, or far enough to give it a wide opening through the apparatus; then the handle 120 is pulled out as far as it will go, which affords a wide opening through the neck 4 from the bin down into the measuring apparatus; then the key is applied to the rear 110 end part 119 of the shaft 117, turning this shaft and causing the auxiliary finger 96 to open the discharge door 44. By this means 115 the discharge door is held open until the entire quantity of commodity is discharged from the bin.

Where a new lot of commodity is put into the bin varying in specific gravity from that 120 contained therein, or if for any reason the specific gravity of the commodity in the bin varies, the bottom 35 is raised or lowered by applying the key to the end part 115 of the stem 64. This adjustment of the bottom 125 is indicated roughly by the pointer 144 traveling along the upright scale 145; but of course the exact adjustment of the bot-

tom is ascertained by measuring out quantities of the commodity and weighing them on a scale until the actual weight agrees with the weight indicated by the pointer 128 of 6 the apparatus.

Should it be necessary to have access to the mechanism, all that is necessary is to close the auxiliary slide 21 and take out the screws that fasten the plate 113 to the sides 10 of the bin and then draw the entire apparatus bodily from the bin, this being very readily done on account of the support provided by the supporting bars 14 and extension bars 15. When the apparatus has been 15 drawn entirely out, it may then be readily lifted off the extension bars and taken to any place where it will be convenient to make the necessary adjustments or repairs.

While I have illustrated and described my 20 invention in considerable detail, it will be understood that numerous modifications are possible, and therefore I do not limit myself to such illustration and description, but what I claim as new and desire to secure by 25 Letters Patent is:

1. In dispensing apparatus, a normally empty measuring compartment comprising a bottom, an end adjustable over said bottom in said compartment from rear to front and 30 from front to rear of the apparatus while said compartment is empty, to create and define an empty measuring space in said compartment, and inlet means and discharge means for the empty measuring space thus 35 created and defined.

2. In dispensing apparatus, a normally empty measuring compartment comprising a bottom, and an end adjustable over said bottom in said compartment from rear to 40 front and from front to rear of the apparatus while said compartment is empty, to create and define an empty measuring space in said compartment, inlet means and discharge means for the empty measuring space 45 thus created and defined, means accessible outside the rear of the apparatus for adjusting said adjustable end, indicating means outside the front of the apparatus, indicating means outside the rear of the apparatus, 50 and means whereby said means for adjusting said end operates both of said indicating means.

3. In dispensing apparatus, a normally empty measuring compartment comprising a bottom and an end adjustable over said 55 bottom in said compartment from rear to front and from front to rear of the apparatus while said compartment is empty, to create and define an empty measuring space in said compartment, inlet and cut-off means for admitting, under the action of gravity, a commodity to the empty measuring space thus created and defined, discharging means 60 distinct from said adjustable end, operating

in a plane substantially at right angles to 65 the line of adjustment of said end at one side thereof, for discharging the commodity from said measuring space under the action of gravity, and means for discharging the commodity from said discharging means at 70 the rear of the apparatus.

4. In dispensing apparatus, a normally empty measuring compartment comprising a bottom, and an end adjustable over said bottom in said compartment from rear to 75 front and from front to rear of the apparatus while said compartment is empty, to create and define an empty measuring space in said compartment, and inlet means and discharging means for the empty measuring 80 space thus created and defined, means accessible outside of the rear of the apparatus for operating said inlet and cut-off means or said discharging means alternatively, and means to prevent concurrent operation of 85 said inlet and cut-off means and discharging means.

5. In dispensing apparatus, a normally empty measuring compartment comprising a bottom, and an end adjustable over said bottom in said compartment from rear to front and from front to rear of the apparatus while said compartment is empty, to create and define an empty measuring space in said compartment, inlet means and discharging 90 means for the empty measuring space thus created and defined, means accessible outside of the rear of the apparatus for operating said inlet and cut-off means or said discharging means alternatively, means to prevent concurrent operation of said inlet and cut-off means and discharging means, and another means accessible outside the rear of the apparatus to operate said discharging means independently of and concurrently 100 with the operation of said inlet and cut-off means.

6. In dispensing apparatus, a normally empty measuring compartment comprising a bottom, and an end adjustable over said 110 bottom in said compartment from rear to front and from front to rear of the apparatus while said compartment is empty, to create and define an empty measuring space in said compartment, inlet and cut-off means for admitting, under the action of gravity, a commodity to the empty measuring space thus created and defined, discharging means distinct from said adjustable end, operating in a plane substantially at right angles to the line of adjustment of said end at one side thereof, for discharging the commodity from said measuring space under the action of gravity, means for discharging the commodity from said discharging means outside the rear of the apparatus, means accessible outside of the rear of the apparatus for operating said inlet and cut-off 120 125

means or said discharging means alternatively, and means to prevent concurrent operation of said inlet and cut-off means and discharging means.

5. In dispensing apparatus, dispensing mechanism, an inclosure in which said dispensing mechanism is inclosed, a supporting bar fixed inside said inclosure, an extension bar mounted on said supporting bar, and 10 means supporting said dispensing mechanism on said extension bar for withdrawal of said dispensing mechanism from said inclosure.

6. In dispensing apparatus, dispensing mechanism, an inclosure in which said dispensing mechanism is inclosed, a supporting bar fixed inside said inclosure, an extension bar mounted on said supporting bar, and means supporting said dispensing mechanism 20 on said extension bar for withdrawal of said dispensing mechanism from said inclosure, and a plate forming one side of said inclosure but attached to and withdrawable with said mechanism.

7. In dispensing apparatus, dispensing mechanism, an inclosure in which said dispensing mechanism is inclosed, a supporting bar fixed inside said inclosure, an extension bar mounted on said supporting bar, and 30 means supporting said mechanism on said extension bar for withdrawal of said dispensing mechanism from said inclosure, a plate forming one side of said inclosure but attached to and withdrawable with said mechanism and connected parts, and means extending through said plate for operating said dispensing apparatus.

8. In dispensing apparatus, a frame, and dispensing means supported by said frame, 40 supply means with which said frame has detachable connection, an inclosure to which said supply means is attached, a supporting bar fixed inside said inclosure, an extension bar mounted on said supporting bar, and 45 means supporting said frame on said extension bar for withdrawal of said frame and connected parts from said inclosure.

9. In dispensing apparatus, a frame, and dispensing means supported by said frame, 50 supply means with which said frame has detachable connection, an inclosure to which said supply means is attached, a supporting bar fixed inside said inclosure, an extension bar mounted on said supporting bar, means 55 supporting said frame on said extension bar for withdrawal of said frame and connected parts from said inclosure, and a plate forming one side of said inclosure but attached to and withdrawable with said frame and 60 connected parts.

10. In dispensing apparatus, a frame, and dispensing means supported by said frame, supply means with which said frame has 65 detachable connection, an inclosure to which said supply means is attached, a supporting

bar fixed inside said inclosure, an extension bar mounted on said supporting bar, and means supporting said frame on said extension bar for withdrawal of said frame and connected parts from said inclosure, a plate 70 forming one side of said inclosure but attached to and withdrawable with said frame and connected parts, and means extending through said plate for operating said dispensing means. 75

11. In dispensing apparatus, a frame composed of upright sides and an upright end fixed to said sides, a bottom having its edges closely adjoining the inner surfaces of said sides and end, a main slide slidable 80 along the upper edges of said sides and over said end, means defining a measuring compartment between said sides, end, slide and bottom, discharging means for said compartment, supply means above said main slide, 85 a neck interposed between said main slide and said supply means, attached to said frame and making close detachable connection with said supply means, an auxiliary slide to close said neck, an inclosure to which 90 said supply means is attached, a supporting bar fixed inside said inclosure parallel with said sides, an extension bar mounted on said supporting bar, and means supporting said frame on said extension bar for withdrawal of said frame and connected parts from said inclosure.

12. In dispensing apparatus, upright sides, an upright end fixed to said sides, a bottom having its edges closely adjoining the inner surfaces of said sides and end, a slide slidable along the upper edges of said sides and over said end, supply means above said slide, a neck interposed between said slide and said supply means, an agitator operatively 100 mounted in said neck, means connected to said agitator and operatively engaging with said slide to operate the agitator when the main slide is operated, an adjustable end defining a measuring compartment under 105 said slide, and means for discharging commodity from said compartment.

13. In dispensing apparatus, a frame composed of upright sides and an upright end fixed to said sides, a bottom having its edges 110 closely adjoining the inner surfaces of said sides and end, a main slide slidable along the upper edges of said sides and over said end, supply means above said main slide, a neck interposed between said main slide and 115 said supply means, attached to said frame and making close detachable connection with said supply means, an auxiliary slide to close said neck, an adjustable end defining 120 a measuring compartment under said main slide, and means for discharging commodity from said compartment.

14. In dispensing apparatus, a frame composed of upright sides and an upright end fixed to said sides, a bottom having its edges 125

5 closely adjoining the inner surfaces of said sides and end, a main slide slidable along the upper edges of said sides and over said end, supply means above said main slide, a
 10 neck interposed between said main slide and said supply means, attached to said frame and making close detachable connection with said supply means, an auxiliary slide to close said neck, an agitator operatively mounted in said neck, and means connected to said agitator and operatively engaging with said main slide to operate the agitator when the main slide is operated, an adjustable end defining a measuring compartment
 15 under said main slide, and means for discharging commodity from said compartment.

17. In dispensing apparatus, a measuring compartment, means to define a measuring space in said compartment, means to admit and discharge a commodity to and from said compartment, a spout to supply commodity independently of said compartment, a closure for said spout, means directly operating upon said closure to open it, and extending outside the apparatus, and a housing for this means, having an opening, and a closure for this opening, which must be moved before access is had to said means for opening
 30 the closure of the spout.

18. In dispensing apparatus, a normally empty measuring compartment comprising a bottom adjustable up and down, means to admit and discharge a commodity to and from said compartment, an end adjustable over said bottom to define a measuring space in said compartment, made up of a flexible curtain, and means to maintain the tension of said curtain as said bottom is adjusted
 40 up and down.

19. In dispensing apparatus, a measuring compartment, means to admit and discharge a commodity to and from said compartment, a fixed end to said compartment, an end adjustable in said compartment to define a measuring space therein, and guides for said adjustable end on the inner sides of said compartment near the means for admitting the commodity, and having their
 50 upper surfaces inclined downward between said sides and with their ends spaced away from said fixed end.

20. In dispensing apparatus, a measuring compartment having a fixed end, a bottom adjustable up and down, a slide movable over said compartment to admit a commodity thereto, and means to discharge the commodity from said compartment, a carriage adjustable along said compartment under
 55 said slide, an adjustable end carried by said carriage along said compartment to create and define a measuring space therein, and being made up of a flexible curtain fixed to and extending down from said carriage,
 60 sheave means under which said curtain

passes, an end plate closely adjoining said curtain and extending down to and closely adjoining said adjustable bottom, and yieldable tension means exerting a tension on said flexible curtain whereby the curtain may
 70 pass under said sheave means and the height of said adjustable end may vary in accordance with the up and down adjustment of said bottom.

21. In dispensing apparatus, a measuring compartment having a fixed end, a bottom adjustable up and down, a slide movable over said compartment to admit a commodity thereto, a carriage adjustable along said compartment under said slide, an adjustable end carried by said carriage along said compartment to create and define a measuring space therein, and being made up of a flexible curtain fixed to and extending down from said carriage, sheave means under
 80 which said curtain passes, an end plate closely adjoining said curtain and extending down to and closely adjoining said adjustable bottom, a yoke supporting said sheave means and said bottom plate, yieldable tension means on said yoke exerting a tension on said flexible curtain whereby the curtain may pass under said sheave means and the height of said adjustable end
 90 may vary in accordance with the up and down adjustment of said bottom.

22. In dispensing apparatus, a measuring compartment having a fixed end, a bottom adjustable up and down, a slide movable over said compartment to admit a commodity thereto, and means to discharge the commodity from said compartment, a carriage adjustable along said compartment under said slide, an adjustable end carried by said carriage along said compartment to create and define a measuring space therein, and being made up of a flexible curtain fixed to and extending down from said carriage, sheave means under which said curtain passes, a yoke supporting said sheave means, yieldable tension means on said yoke exerting a tension on said flexible curtain whereby the curtain may pass under said sheave means and the height of said adjustable end may vary in accordance with the up and down adjustment of said bottom,
 100 means on said carriage to guide said yoke up and down with said bottom, and means on said bottom to guide said yoke along said
 105 bottom with said carriage.

23. In dispensing apparatus, a measuring compartment having a fixed end, a bottom adjustable up and down, a slide movable over said compartment to admit a commodity thereto, and means to discharge the commodity from said compartment, a carriage adjustable along said compartment under said slide, an adjustable end carried by said carriage along said compartment to create and define a measuring space therein, and
 110 120
 125
 130

being made up of a flexible curtain fixed to and extending down from said carriage, sheave means under which said curtain passes, an end plate closely adjoining said curtain and extending down to and closely adjoining said adjustable bottom, a yoke supporting said sheave means and said bottom plate, yieldable tension means on said yoke exerting a tension on said flexible curtain whereby the curtain may pass under said sheave means and the height of said adjustable end may vary in accordance with the up and down adjustment of said bottom, means on said carriage to guide said yoke up and down with said bottom, and means on said bottom to guide said yoke along said bottom with said carriage.

24. In dispensing apparatus, a measuring compartment having a fixed end, a bottom, a slide movable over said compartment to admit a commodity thereto, and means to discharge the commodity from said compartment, and an end adjustable along said compartment under said slide, a rack connected to said adjustable end parallel with its direction of adjustment, a shaft journaled on said apparatus and extending toward the front and rear thereof, a bevel gear fixed on said shaft, another bevel gear meshing with this bevel gear, and a spur gear turning with this other bevel gear and meshing with said rack, and handle means for turning said shaft.

25. In dispensing apparatus, a measuring compartment having a fixed end, a bottom, a slide movable over said compartment to admit a commodity thereto, and means to discharge the commodity from said compartment, and an end adjustable along said compartment under said slide, a rack connected to said adjustable end parallel with its direction of adjustment, a shaft journaled on said apparatus and extending toward the front and rear thereof, a bevel gear fixed on said shaft, another bevel gear meshing with this bevel gear, and a spur gear turning with this other bevel gear and meshing with said rack, handle means for turning said shaft, and friction means for retarding the turning of said shaft.

26. In dispensing apparatus, a measuring compartment having a fixed end, a bottom, a slide movable over said compartment to admit a commodity thereto, and means to discharge the commodity from said compartment, and an end adjustable along said compartment under said slide, a rack connected to said adjustable end parallel with its direction of adjustment, a shaft journaled on said apparatus and extending toward the front and rear thereof, a bevel gear fixed on said shaft, another bevel gear meshing with this bevel gear, and a spur gear turning with this other bevel gear and meshing with said rack, handle means

for turning said shaft, a stationary disk, a disk turning with said shaft, a spring normally pressing the disks together, and means whereby said handle means may be caused to separate said disks. 70

27. In dispensing apparatus, a measuring compartment having a fixed end, a bottom, a slide movable over said compartment to admit a commodity thereto, and means to discharge the commodity from said compartment, and an end adjustable along said compartment under said slide, a rack connected to said adjustable end parallel with its direction of adjustment, a shaft journaled on said apparatus and extending 75 toward the front and rear thereof, a bevel gear fixed on said shaft, another bevel gear meshing with this bevel gear, and a spur gear turning with this other bevel gear and meshing with said rack, handle means for 80 turning said shaft, a gear turning with said shaft, a pointer pivoted on said apparatus, a gear with which said pointer turns, meshing with the gear on the shaft, and a scale upon which said pointer indicates the 85 adjustment of said adjustable end.

28. In dispensing apparatus, a normally empty measuring compartment comprising a bottom, and an end adjustable over said bottom in said compartment from rear to 95 front and from front to rear of the apparatus while said compartment is empty, to create and define an empty measuring space in said compartment, a discharge outlet from said compartment, inlet and cut-off 100 means for admitting, under the action of gravity, a commodity to the empty measuring space thus created and defined, a lever fulcrumed on said apparatus, with one end part connected to said inlet and cut-off 105 means, and an inlet and discharge rod slideable toward the front and rear of the apparatus and pivotally connected to said lever.

29. In dispensing apparatus, a normally empty measuring compartment comprising 110 a bottom, and an end adjustable over said bottom in said compartment from rear to front and from front to rear of the apparatus while said compartment is empty, to create and define an empty measuring space 115 in said compartment, a discharge outlet in said compartment, cut-off means for admitting, under the action of gravity, a commodity to the empty measuring space thus created and defined, a lever fulcrumed on 120 said apparatus, with one end part connected to said inlet and cut-off means, an inlet and discharge rod slideable toward the front and rear of the apparatus and pivotally connected to said lever, but rotatable in its connection therewith, a discharge door to close 125 said discharge outlet, and operative connection from said rod to said door whereby the opening and closing of said outlet is controlled by turning said rod. 130

30. In dispensing apparatus, a normally empty measuring compartment comprising a bottom, and an end adjustable over said bottom in said compartment from rear to front and from front to rear of the apparatus while said compartment is empty, to create and define an empty measuring space in said compartment, a discharge outlet in said compartment, inlet and cut-off means for admitting, under the action of gravity, a commodity to the empty measuring space thus created and defined, a lever fulcrumed on said apparatus, with one end part connected to said inlet and cut-off means, an inlet and discharge rod slidable toward the front and rear of the apparatus and pivotally connected to said lever, but rotatable in its connection therewith, a discharge door to close said discharge outlet 70 means for admitting, under the action of gravity, a commodity to the empty measuring space thus created and defined, a lever fulcrumed on said apparatus, with one end part connected to said inlet and cut-off means, an inlet and discharge rod slidable toward the front and rear of the apparatus and pivotally connected to said lever, but rotatable in its connection therewith, a discharge door to close said discharge outlet 75 means for admitting, under the action of gravity, a commodity to the empty measuring space thus created and defined, a lever fulcrumed on said apparatus, with one end part connected to said inlet and cut-off means, an inlet and discharge rod slidable toward the front and rear of the apparatus and pivotally connected to said lever, but rotatable in its connection therewith, a discharge door to close said discharge outlet 80 means for admitting, under the action of gravity, a commodity to the empty measuring space thus created and defined, a lever fulcrumed on said apparatus, with one end part connected to said inlet and cut-off means, an auxiliary finger constantly in position for engagement with said operating bar, and means to move said auxiliary finger to open said outlet independently of and concurrently with the opening of said inlet and cut-off means.

25 31. In dispensing apparatus, a normally empty measuring compartment comprising

30 a bottom, and an end adjustable over said bottom in said compartment from rear to front and from front to rear of the apparatus while said compartment is empty, to create and define an empty measuring space 35 in said compartment, a discharge outlet in said compartment, inlet and cut-off means for admitting, under the action of gravity, a commodity to the empty measuring space thus created and defined, a lever fulcrumed 40 on said apparatus, with one end part connected to said inlet and cut-off means, an inlet and discharge rod slidable toward the front and rear of the apparatus and pivotally connected to said lever, but rotatable in 45 its connection therewith, a discharge door to close said discharge outlet, an operating bar connected to said door, a finger fixed on said rod to push on said operating bar when said rod holds the inlet and cut-off means 50 closed, and thereby opens said outlet, but being moved out of position for engagement with said operating bar when said rod opens said inlet and cut-off means, and a guard with which said finger engages to prevent 55 turning of said rod, when the finger is out of position for engagement with said operating bar.

32. In dispensing apparatus, a normally empty measuring compartment comprising

60 a bottom, and an end adjustable over said bottom in said compartment from rear to front and from front to rear of the apparatus while said compartment is empty, to create and define an empty measuring space 65 in said compartment, a discharge outlet in

said compartment, inlet and cut-off means for admitting, under the action of gravity, a commodity to the empty measuring space thus created and defined, a lever fulcrumed on said apparatus, with one end part connected to said inlet and cut-off means, an inlet and discharge rod slidable toward the front and rear of the apparatus and pivotally connected to said lever, but rotatable in its connection therewith, a discharge door to close said discharge outlet, an operating bar connected to said door, a finger fixed on said rod to push on said operating bar when said rod holds the inlet and cut-off means closed, and thereby opens said outlet, but being moved out of position for engagement with said operating bar when said rod opens said inlet and cut-off means, an auxiliary finger constantly in position for engagement with said operating bar, and means to move said auxiliary finger to open said outlet independently of and concurrently with the opening of said inlet and cut-off means.

33. In dispensing apparatus, a normally empty measuring compartment comprising a bottom, and an end adjustable over said

bottom in said compartment from rear to front and from front to rear of the apparatus while said compartment is empty, to create and define an empty measuring space in said compartment, a discharge outlet in said compartment, inlet and cut-off means for admitting, under the action of gravity, a commodity to the empty measuring space thus created and defined, a lever fulcrumed on said apparatus, with one end part connected to said inlet and cut-off means, an inlet and discharge rod slidable toward the front and rear of the apparatus and pivotally connected to said lever, but rotatable in its connection therewith, a discharge door to close said discharge outlet, an operating bar connected to said door, a finger fixed on said rod to push on said operating bar when said rod holds the inlet and cut-off means closed, and thereby open said outlet, but being moved out of position for engagement with said operating bar when said rod opens said inlet and cut-off means, a guard with which said finger engages to prevent turning of said rod when the finger is out of position for engagement with said operating bar, and an auxiliary finger constantly in position for engagement with said operating bar, and means to move said auxiliary finger to open said outlet independently of and concurrently with the opening in said inlet and cut-off means.

34. In dispensing apparatus, a normally empty measuring compartment comprising a bottom, and an end adjustable over said bottom in said compartment from rear to front and from front to rear of the apparatus while said compartment is empty, to

create and define an empty measuring space in said compartment, a discharge outlet at one side of said compartment, inlet and cut-off means for admitting, under the action of gravity, a commodity to the empty measuring space thus created and defined, operated by sliding from rear to front and from front to rear of the apparatus, operating means for said inlet and cut-off means, a rack connected to said adjustable end parallel with its direction of adjustment, a shaft journaled on said apparatus and extending toward the front and rear thereof, a bevel gear fixed on said shaft, another bevel gear mesh-

ing with this bevel gear, and a spur gear 15 turning with this other bevel gear and meshing with said rack, handle means for turning said shaft, a discharge door hinged on said shaft to close said discharge outlet, and an operative connection from the operating means of the inlet and cut-off means to said door, whereby the opening and closing of said outlet is controlled by said operating means. 20
